UNITED STATES PATENT OFFICE.

WALTER J. SPIRO, OF WHITE PLAINS, NEW YORK.

METALLIC STRUCTURE FOR RUNNING-BOARDS.

1,334,565.

Specification of Letters Patent. Patented Mar. 23, 1920.

Application filed July 26, 1919. Serial No. 313,470.

To all whom it may concern:

Be it known that I, WALTER J. SPIRO, citizen of the United States, residing at White Plains, in the county of Westchester 5 and State of New York, have invented certain new and useful Improvements in Metallic Structures for Running-Boards, of which the following is a specification.

This invention relates to a metallic structure for running boards and particularly to the construction of the running board tread or mat and the binding molding for retaining the same in position.

The invention has for an object to provide a novel and improved bi-metal structure composed of a sheet metal base and a superposed layer of noncorrosive sheet metal inclosing the base and secured thereto.

A further object of the invention is to provide a construction comprising closely contacting layers of different sheet metals having raised portions upon the tread face thereof stamped or pressed from the contacting layers so as to nest the same together.

Another object of the invention is to provide an improved form of metallic molding for a running board consisting of an angular sheet metal base having a noncorrosive sheet metal covering bent over the opposite edges thereof and formed with projections at the tread portion pressed from both layers of material.

Other and further objects and advantages 35 of the invention will be hereinafter set forth and the novel features thereof defined by the appended claims.

In the drawing—

Figure 1 is a perspective showing the 40 running board;

Fig. 2 is an enlarged detail sectional perspective, and Fig. 3 is a vertical section showing a modified application of the invention.

Like numerals refer to like parts in the figures of the drawing.

The numeral 10 designates the tread or mat of a running board which is herein shown as formed from a sheet metal base 50 plate 11 of iron, steel or similar material of proper thickness to secure the desired strength and rigidity and may be supported in any desired manner. This base is covered and inclosed by a sheet 12 of noncorrosive metal, such as aluminum, which is secured thereto at its opposite sides by the

overbent portions 13 embracing the edges of the base. These plates when assembled may be provided with any desired character of projections upon their upper or 60 tread face, for instance as shown at 14 where they are pressed from both layers of material and are preferably of pyramid form or design. Such a tread or mat may be retained in position by any suitable 65 form of edge molding or binding, formed independent thereof or integral therewith.

A preferred form of such molding is herein disclosed and it may be used with a mat of any character or material. This 70 molding comprises a base 15 of sheet material such as iron or steel of proper weight to provide the desired strength and rigidity. The base is of angular form and consists of the upper or tread face 16 and the front 75 face 17 having at its lower edge an offset 18. The outer faces of the base are completely covered by a layer 19 of noncorrosive sheet metal, such as aluminum, and the side or longitudinal edges of this covering are 80 bent over the corresponding edges of the base, as shown at 20, to inclose the same and retain the covering in position. The tread face of such molding are usually provided with ribs or projections and in the present 85 construction they are formed from both layers of material and comprise corrugations as indicated at 21, which by nesting together bind the base in close contact or formation to prevent any movement thereof 90 upon each other. Any desired character of projections may be formed upon the molding and it may be secured in position to retain the mat by any form of fastening device, such as shown at 22. For this purpose the molding may be provided with an 95 inturned flange 23 at its lower portion.

In Fig. 3 a very desirable attaching means for the molding is shown. The base or support 24 for the mat or cover 25 may be of 100 any preferred material, for instance wood, and the edges of the mat are secured thereto by an attaching strip 26 having a corrugated upper face 27 and a front face 28. This strip is secured by fastening devices 29 extending 105 therethrough and through the mat into the support. The corrugated face of the strip nests or fits into the contacting corrugated face of the molding and thus retains the latter against lateral movement thereon, 110 while the lower edge of the molding is attached to the support by the fastening de-

2
vices 22 extending through the flange 23. While the face of the strip and molding are shown as corrugated, other forms of projections or raised sections may be used and 5 arranged to nest together or interlock for the same purpose. This attaching means entirely conceals the fastening devices and stiffens the tread face of the molding at the points of greatest wear so that a lighter 10 weight of molding may be used than would be otherwise necessary.

In the construction of both the mat and molding the noncorrosive face layer embraces the longitudinal edges of the base 15 and when the ribs or projections are pressed from both layers any slack between the same is taken up and a firm intimate contact secured which effectually preserves the base metal from corrosion and provides a tread 20 or wearing surface of sufficient thickness to overcome the objections to a plated or coated surface. The invention presents a bi-metal structure of proper rigidity and attractive design in which a noncorrosive wearing 25 surface of the desired thickness is firmly secured to the base by the raised sections pressed from the assembled sheets of material which also offer resistance to slippage of the foot in the use of the running board. 30 The invention presents a simple, efficient and economically constructed form of mat and molding for the step or running board, of any type of automobile or other vehicle.

What I claim is—

- 35 1. A metallic edge molding structure for running boards consisting of an angular base of sheet metal and a sheet metal covering layer inclosing the same and secured thereto at its opposite edges.
- 40 2. A metallic tread surface for running boards consisting of a sheet metal base and a sheet metal covering secured thereto at its edges, both of which layers are provided with raised sections closely nested together.
- 45 3. A metallic tread surface for running boards consisting of a sheet metal base, a noncorrosive sheet metal covering bent over the opposite edges thereof, and raised sections at the tread portion formed from both

layers of material whereby the covering is 50 brought into close contact with the base.

4. A metallic edge molding for running boards consisting of an angular sheet metal base having an offset at the lower edge of its front face, a noncorrosive sheet metal layer 55 completely covering the outer face of said base and embracing the opposite side edges thereof, and a corrugated tread face formed from both layers of material.

5. A metallic edge molding for running 60 boards consisting of an angular sheet metal base, a noncorrosive sheet metal covering secured to the opposite side edges thereof, raised sections formed from both layers of 65 material at their tread face, and an attaching flange disposed at the lower edge of said base.

6. A metallic edge molding for running 70 boards consisting of an angular sheet metal base, a noncorrosive sheet metal covering 75 secured in direct contact therewith, raised sections formed from both layers of material at their tread face, an attaching flange disposed at the lower edge of said base, and an attaching strip disposed beneath the 75 tread portion of the molding and adapted to interlock therewith.

7. A metallic edge molding for running 80 boards consisting of an angular sheet metal base, a noncorrosive sheet metal covering 85 secured in direct contact therewith, raised sections formed from both layers of material at their tread face, and an attaching strip disposed beneath the tread portion of the molding and formed to interlock with 85 the raised sections thereof.

8. A metallic edge molding for running 90 boards consisting of an angular sheet metal base, a noncorrosive sheet metal covering 95 secured to the opposite side edges thereof, corrugations formed from both layers of material at their tread face, a support, and an attaching strip having a corrugated upper face secured to the support and nesting in the corrugations of the tread portion.

In testimony whereof I affix my signature.

WALTER J. SPIRO.
